UNITED STATES PATENT OFFICE.

WILLIAM HELFENBERGER, GEORGE W. KILER, AND CHARLES M. KILER, OF INDIANAPOLIS, INDIANA.

FENCE-POST.

SPECIFICATION forming part of Letters Patent No. 394,854, dated December 18, 1888.

Application filed November 9, 1887. Serial No. 254,687. (No model.)

To all whom it may concern:

Be it known that we, WILLIAM HELFENBERGER, GEORGE W. KILER, and CHARLES M. KILER, citizens of the United States, residing 5 at Indianapolis, in the county of Marion and State of Indiana, have invented a new and useful Improvement in Fence-Posts, of which the following is a specification.

Our invention relates to improvements in 10 fence-posts of the class in which the posts consist of two parts, one of which is metal and forms the base which is driven into the earth, and the other part of which is wood and which is adjustably secured to the base.

15 In usual fence-posts of this construction considerable difficulty has been experienced in making the wooden part of the post adjustable with relation to the base and retain in the different positions of adjustment a close 20 contact and solid bearing between the post and base for the full width of the post, which is a material advantage, and is essential to the proper construction of an adjustable fence-post, and the accomplishment of this is one 25 of the chief objects of our invention.

Another object of our invention is to produce a composite post of the class mentioned which will bear driving without disconnecting its parts, which may be aligned or set 30 plumb and securely fixed in position before driving, may be differently adjusted after the base is driven into the earth, and which may be cheaply manufactured.

The invention consists in the special construction and arrangement of the parts of the post, substantially as hereinafter described and claimed.

In the drawings, Figure 1 represents in side elevation our improved fence-post; Fig. 2, a 40 side elevation opposite to that shown in Fig. 1; Fig. 3, a front elevation; and Fig. 4 is a plan view of the base.

The base consists of a casting having the three radially-arranged longitudinal flanges *a b c*, which are tapering, as shown, a vertically-projecting lug, *e*, having at its lower end or at the upper terminus of the radial flanges *a b c* a convexed post-supporting flange, *d*, projecting out at right angles there- 45 to and extending the entire width of the lug *e*, for the purpose hereinafter set forth, said

flange *d* connecting the flanges *a b c* at the tops, one of said flanges, as shown, terminating directly central with relation to the outer edges of said convex flange *d*, thus forming a 55 central support therefor and securing the maximum amount of strength at the points where it is needed with the minimum amount of material.

The vertical web or lug *e*, projecting upwardly from the rear edge of the convex flange *d*, is arranged parallel with a line drawn across the outer edges of two of the adjacent flanges.

The flanges *a b c*, the vertical lug *e*, and post-supporting convexed flange *d* are all cast 65 in one piece.

The vertical lug *e* has formed therein near its upper end a curved transverse slot, *f*, which is concentric with the convex upper surface of the post-supporting flange *d*, and 70 has projecting from its inner face one or more points or barbs, *i i*, to project into and hold the wooden post when clamped into adjusted position.

The lower bearing end of the wooden post 75 *P* is concaved to correspond to the convexity of the upper surface of the supporting-flange *d*, upon which it rests. This construction of the lower end of the wooden post and the upper surface of its supporting-flange insures a 80 continuous and close bearing the full width of the post in all its adjusted positions, which is a great desideratum, it maintaining a wide solid bearing, obviating looseness, and, in consequence of its close contact, in a measure prevents 85 the admission of water to rust or rot and weaken the bearing. The post in practice will be made narrower than the full width of the convex bearing-flange *d*. This arrangement forms practically a ball-and-socket con- 90 nection between the base and wooden post, and the bearing strain upon the flange *d* and end of the post is equal at all points.

The purpose of the convex upper surface of the flange *d* and concaved lower end of the 95 wooden post *P* and the curved slot *f* is also to allow the lateral adjustment of the wooden post after the base has been set, as indicated by the dotted line in Fig. 1, the lower concaved end of the wooden post resting at all 100 times solidly upon the convex -surfaced flange *d*.

In operation, the wooden post having been secured to the base by the bolt *h*, which passes the curved slot *f* in the lug *e* and through the said post, the base is set so that one edge of the wooden post shall be on a line of the proposed fence, and in case of a wire fence that part of the base from which lug *e* rises shall be toward the side from which the wires are to be strained, thus presenting the re-entrant angle formed by two of the flanges at right angles to the line of draft. The base is then driven into the earth by blows upon the top of the post, the lower end of the post resting solidly on the upper convex face of the supporting-flange *d*. After the base has been driven the vertical alignment of the post is effected by loosening the bolt *h* and swinging the post laterally outward or inward, as may be required, the lower concaved end of the post resting and turning upon the convex-surfaced flange *d*.

We claim—

1. A composite fence-post consisting of the tapered radially-flanged base having the vertical lug or web *e* at its upper end, with the curved slot *f* therein, said lug having the barbs *i* projecting outward, as described, the convex-surfaced flange *d*, projecting from the lower end of the lug *e* at right angles and ex-

tending across the upper ends of the radial flanges of the base, the curve of the flange *d* being concentric to the curved slot *f*, and the wooden post *P*, concaved at its lower end to correspond to the convexity of the supporting-flange, and a bolt, *h*, to extend through the post and curved slot in the lug *e*, to secure the parts together, all substantially as and for the purpose described.

2. A fence-post comprising the base, consisting of the three tapered radial longitudinal flanges *a b c*, the post-supporting plate or flange *d*, convexed at its upper surface and extending horizontally entirely over and formed contiguous with the upper ends of the three longitudinal flanges, and having the vertical lug or web *e* extended up from one edge thereof, with the curved slot formed therein, as described, and the wooden post *P*, concaved at its lower end and resting its full width upon the convex flange *d*, and the bolt *h*, to secure the parts together, substantially as and for the purpose set forth.
